UNITED STATES PATENT OFFICE

VERL E. MCCOY, OF MILWAUKEE, WISCONSIN, ASSIGNOR TO LYNDON F. WILSON, OF CHICAGO, ILLINOIS

BOILER FEED APPARATUS

Application filed February 13, 1930. Serial No. 428,011.

This invention pertains to methods and apparatus for preheating boiler feed water and is particularly well adapted for use with locomotives.

5 It is important that feed water supplied to a locomotive already fired up be not so low in temperature as to set up unequal strains within the boiler and cause destruction of the boiler plates, hence various means 10 have been adopted for preheating the feed water. In the prior patent applications of Lyndon F. Wilson covering feed water conditioners, one of which applications was filed July 30, 1928, and another filed October 10, 15 1929, apparatus for preheating feed water has been shown. This invention may be used, if desired, in conjunction with the disclosures of either of those prior patent applications.

This invention contemplates the use of a 20 preheater mounted on the locomotive adjacent the point of injection of the feed water. Though the feed water in the supply pipe leading from the tender forwardly may become chilled in winter weather, by means of 25 this invention it is precluded from entering the boiler until it has been restored to or has attained a predetermined desired feed water temperature.

The several objects of this invention and 30 means of attaining them will be more fully set forth hereinafter.

In the drawing:

Fig. 1 is a side elevation of a locomotive equipped with one form of the invention, 35 and

Fig. 2 is a side elevation of a locomotive equipped with another form of the invention.

Referring particularly to Fig. 1 of the drawing a locomotive 1 is provided with a tender 2 in which a supply of feed water is stored in the usual manner. The exhaust from the steam cylinders is conducted through a pipe 3 to the tender where it is mingled with the water in any suitable manner, preferably in the manner disclosed in

either of the above mentioned two patent applications. The heated water from the tender is withdrawn therefrom through a pipe 4, and the turbo-pump 5, driven by a small steam turbine, forces the water through the 50 pipe 6, preheater 7 and pipe 8 into the boiler. The preheater may be an open type or closed type heater, the latter being shown.

In accordance with the usual practice the engine crew, whenever feed water is required in the boiler will open the valve 9 in the live steam line 11 and supply steam to the turbo-pump to drive the same and pump water from the tender into the boiler. If the water in the preheater tank 7 or the water passing therethrough is at a temperature lower than any predetermined desired temperature the thermostat 12 will actuate the thermostatic valve 13 to open the same and permit live steam to be injected through the pipe 14 into 60 the preheater tank. This injection will continue until the water temperature will cause the thermostatic valve to be closed. In this manner the feeding of the boiler with water of too low a temperature is prevented. 70

The pipe 8 is provided with a check valve 15 which will admit water to the boiler but prevent reverse flow. The preheater 7 is provided with tubes 16 through which the water flows between the header chambers 17 and 18. The exhaust steam line 3 is provided with a check valve 19 and has a branch line 20 which admits exhaust steam to the space about the tubes 16. The condensate is conducted through the line 21 and check valve 22 80 to the intake side of the pump.

Referring now to Fig. 2 a locomotive 1' and a tender 2' are provided with the exhaust steam line 3' for conducting steam into the water supply in the tender for heating the 85 same. The heated water is withdrawn from the tender through the pipe 4' and delivered by the turbo-pump 5' through the pipe 6' into a preheater tank 7', thence through the pipe 8' into the boiler. The hand valve 9' 90

will be regulated by the engine crew to provide intermittent or continuous operation of the turbo-pump 5' by supplying live steam from the live steam supply line 11' to the turbo-pump.

5 The preheater tank 7' will be preferably a closed type heater having a header chamber 17' into which the feed water is pumped and a header chamber 18' from which the water flows into the pipe 8'. These two header chambers are connected together by tubes 16' through which the feed water flows. Part of the exhaust steam from the line 3' is conducted by the pipe 20' into the space surrounding the water tubes 16' to supply thereby heat to the feed water. The condensate received from the exhaust steam is returned through the pipe 21', through the check valve 22' and is conducted back into the water tender where it may mingle with the feed water.

The pipe 8' is provided with a check valve 15' which will permit flow therethrough only into the boiler while the exhaust steam line 3' is provided with a check valve 19' for permitting flow of the exhaust steam only rearwardly.

33 The thermostat bulb 23 is inserted into the water which lies in or passes through the header chamber 18' and whenever the feed water temperature at that point is lower than a certain predetermined desirable temperature the thermostatic element will cause the closing of the thermostatic valve 24 which will thereby close the live steam supply line to the turbo-pump whether or not the valve 9' is open. In this manner assurance is given that water of too low temperature cannot be forced by the turbo-pump through the preheater tank 7' into the boiler. When the water temperature in the preheater tank 7' is brought up to the right temperature by the exhaust steam the thermostatic valve 24 will be re-opened and the engine crew will be able to start and regulate the operation of the turbo-pump by means of the valve 9', and the pump operation will be continued so long as the feed water passing through the preheater tank does not, by reason of having too low a temperature, cause the thermostatic valve 24 to be closed.

It should be understood that this invention is susceptible of embodiment in various other modifications which may differ from the present disclosure.

Having shown and described this invention, I claim:

1. In combination with a boiler and a feed water storage tank, a steam driven pump and pipe line connected for delivering water from the tank into the boiler, a preheating chamber disposed in said pipe line, means for delivering exhaust steam to said chamber for preheating the water, and thermostatic means including a thermostatic element disposed in

said chamber constructed for controlling the supply of live steam to said pump arranged to prevent delivery from said chamber into the boiler of water having less than a predetermined temperature.

70

2. In combination with a locomotive boiler and a feed water storage tank, means for utilizing the cylinder exhaust steam for heating the water in said storage tank, a pump and pipe line connected for delivering water from said tank into the boiler, a preheating chamber interposed in said line adjacent its connection with the boiler and means for supplying steam thereto, and means including a thermostatic element disposed in said chamber constructed for thermostatically controlling starting of the pump to prevent delivery from said chamber of water having less than a predetermined temperature.

75

3. In combination with a locomotive boiler and a feed water storage tank, means for utilizing the cylinder exhaust steam for heating the water in said storage tank, a pump and pipe line connected for delivering water from said tank into the boiler, a preheating chamber interposed in said line adjacent its connection with the boiler and means for supplying steam thereto, and means independent of the first said means including a thermostatic element disposed in said chamber constructed for thermostatically controlling starting of the pump to prevent delivery from said chamber of water having less than a predetermined temperature.

80

4. In combination with a locomotive boiler and a tender tank for storing feed water, a pump and pipe line constructed for delivering water from said tank into the boiler, means for utilizing the cylinder exhaust steam for preheating the water in said tank, an auxiliary preheating chamber disposed in said pipe line adjacent the inlet thereof into the boiler and a pipe for supplying steam to said chamber for preheating of the water therein, and means including a thermostatic element disposed in said chamber constructed for thermostatically controlling starting of the pump to prevent delivery from the chamber into the boiler of water having less than a predetermined temperature.

85

5. In combination with a locomotive boiler and a feed water storage tank, a pump and pipe line connected for delivering water from the tank into the boiler, a preheating chamber interposed in said line adjacent its connection with the boiler, means for conducting cylinder exhaust steam to said chamber for heating the water therein, and means independent of the first said means including a thermostatic element disposed in said chamber constructed for thermostatically controlling starting of the pump to prevent delivery from said chamber of water having less than a predetermined temperature.

90

6. The method of preheating and supply-
